UNITED STATES PATENT OFFICE.

WARD S. PERRY, OF CHICAGO, ILLINOIS, ASSIGNOR TO VESTA ACCUMULATOR COMPANY, OF CHICAGO, ILLINOIS, A CORPORATION OF ILLINOIS.

CONNECTOR FOR BATTERIES.

1,288,160.

Specification of Letters Patent.

Patented Dec. 17, 1918.

Application filed April 9, 1917. Serial No. 160,845.

To all whom it may concern:

Be it known that I, WARD S. PERRY, a citizen of the United States, and a resident of the city of Chicago, in the county of Cook 5 and State of Illinois, have invented certain new and useful Improvements in Connectors for Batteries, of which the following is a specification, reference being had to the accompanying drawings.

10 My invention relates to connectors for batteries and particularly to a form of device suitable for connecting lead wires to a storage battery in an electric lighting and starting mechanism for an automobile. The acid 15 fumes rising from an ordinary lead plate storage battery render it necessary to give the battery attention from time to time in order to insure proper working efficiency, and it is quite frequently necessary to re- 20 move an old battery and to substitute another in its place. Inasmuch as there is in different automobiles a great variety of differing conditions in the matter of the size and position of the plugs of the lead wires, 25 it is highly important that a service station dealing in batteries and giving battery service shall either carry a correspondingly great variety of equipment or shall be in a position otherwise to meet quickly and easily the 30 varied demands to be made upon the service. It is the principal object of my invention to provide a form of connector which shall be capable of adjustment to almost any combination of conditions and which in any combination shall be capable of being readily applied without any unnecessary delay whereby it is made unnecessary for a service station 35 to carry in stock any great supply of batteries in order to render the desired 40 prompt service. It is another object of my invention to provide a form of connector which shall be highly efficient and which shall at the same time be capable of being produced cheaply and readily. It is still 45 another object of my invention to improve devices of this type in sundry details herein-after pointed out. The preferred means by which I have accomplished my several objects are illustrated in the accompanying 50 drawings and are hereinafter specifically described. That which I believe to be new

and desire to cover by this application is set forth in the claims.

In the drawings:

Figure 1 is a plan view of a battery 55 equipped with my improved connectors and showing in dotted lines changed positions of the lead wires and connectors;

Fig. 2 is a view similar to Fig. 1, but showing the connectors in inverted position so as 60 to meet still other changed conditions;

Fig. 3 is a side view showing one of my connectors in position upon the binding post of a battery; and

Fig. 4 is a top view of the connector shown 65 in Fig. 3.

Referring to the several figures of the drawings, in which corresponding parts are indicated by the same reference characters,—

70 10 indicates a storage battery of the ordinary lead plate type, comprising permanent connectors 11—12 connecting binding posts 13 of opposite polarity upon the several cells making up the battery. The binding 75 posts 13 and the connectors 11—12 are preferably formed of lead or are at least lead coated so as to be capable of resisting the fumes from the acid within the battery. The connectors 11—12 are preferably burned 80 or soldered in position upon the binding posts 13. The terminal binding posts of the battery are indicated by the numerals 14—15, being also preferably formed of lead and having suitably connected thereto the lead 85 wires 16—17 which serve for charging and discharging the battery as is fully understood.

80 The connectors for the lead wires 16—17 comprise split sleeves or rings 18 the inner 90 faces of which are provided with a double taper as is indicated by dotted lines in Fig. 3, whereby a portion of the inner face of the sleeve has a snug fit upon the binding post whether the connector is in position as is 95 shown in Fig. 2, or is placed in inverted position as shown in Fig. 1. As is best shown in Fig. 4, the split ring 18 has its end portions 19—20 turned into parallelism. The heavier end portion or arm 20 is provided 100 with a tapered socket adapted to furnish a snug fit for a terminal plug 21

which is inserted therein, the plug 21 in the construction shown being provided with a socket 22 for the connection of a lead wire thereto. The plug 21 is held in position in its socket in the arm or end portion 20 of the split ring 18 by means of a screw 23 which passes through a suitable opening in the arm or end portion 19 into engagement with a screw-threaded opening 24 in the end of the plug. As will be readily understood, by tightening up the screw 23 the plug 21 is drawn very forcibly into contact with the face of the socket in the end portion 20, and the arms 19-20 are drawn very forcibly toward each other whereby the ring 18 is caused to grip very tightly upon the binding post 14.

As will be readily understood, by loosening the screw 23, the connector can be shifted to any desired angular position about the central longitudinal line of the binding post 14 so as to be adapted to receive the lead wires from any direction. The connector as a whole is also adapted to be inverted and secured just as strongly upon the binding post in such inverted position so as to be capable of meeting either such conditions as are illustrated in Fig. 2 or such conditions as are illustrated in dotted lines in Fig. 1. It will be understood that the connector in either of its inverted positions is equally capable of angular adjustment about the binding post.

The sleeve 18 of my improved connector is preferably formed of lead without a strengthening core of any other metal, and I have found in practice that this expedient is highly efficient. While the sleeve has little if any resilience, it can be bound just as securely in position by pressure upon the arms or end portions 19-20. When the sleeve is removed from the binding post, it can be spread apart readily by reason of the softness of the material without having to rely upon any resilience of the metal. Also by reason of the readiness with which the sleeve is bent as desired, the sleeve is caused to have a very snug fit upon the binding post regardless of any irregularities in the conformation of the post.

By the use of my improved connector, I am enabled very quickly and easily to meet a great variety of conditions without the delay which results from the necessity for burning on the connector as has been the general practice heretofore when a battery provided for one set of conditions has been changed over to meet another set of conditions. So far as I am aware, I am the first in the art to provide a construction in which the screw which secures the plug in the socket of the connector serves also to secure the connector upon the binding post of the battery, and my claims are to be construed accordingly.

Moreover, so far as I am aware, I am the first in the art to provide a connector comprising a split ring or sleeve made of lead adapted to be secured upon the binding post of a battery by pressure applied upon the end portions of the split sleeve, through the medium of the terminal plug, being able thus to dispense with the use of a strengthening core of other metal, and I therefore wish to claim this feature broadly.

What I claim as my invention and desire to secure by Letters Patent, is—

1. A connector comprising a split ring having substantially parallel end members, one of said members having a tapered socket, a tapered plug fitted in said socket, and binding means mounted in the other member and operatively engaging said plug, whereby said binding means operates to draw said plug into said socket and also contracts said split ring.

2. A connector comprising a split ring having substantially parallel end members, one of said members having a tapered socket, a tapered plug fitted in said socket, and a screw carried by the other member and fitting in a threaded socket in said plug, whereby said screw operates to draw said plug into said tapered socket and also contracts said split ring.

3. A connector comprising a split ring having a conical inner surface and substantially parallel end members, one of said members having a tapered socket, a tapered plug fitted in said socket, and binding means mounted in the other member and operatively engaging said plug, whereby said binding means operates to draw said plug into said socket and also contracts said split ring.

4. A connector comprising a split ring having a conical inner surface and substantially parallel end members, one of said members having a tapered socket, a tapered plug fitted in said socket, and a screw carried by the other member and fitting in a threaded socket in said plug, whereby said screw operates to draw said plug into said tapered socket and also contracts said split ring.

5. A connector comprising a split ring having a tapered inner surface and having substantially parallel end members, and means coöperating with said members for varying the diameter of said split ring.

6. The combination of a tapered plug of a reversible connector comprising a split ring adapted to fit upon said plug, said ring having its inner surface tapered oppositely toward its margins and having substantially parallel end members, and means coöperating with said end members for varying the diameter of said split ring.

7. A connector comprising a split ring having a conical inner surface and substan-

tially parallel end members, one of said members having a tapered socket, a tapered plug fitted in said socket, and binding means carried by the other member and operatively engaging said plug, whereby said binding means operates to draw said plug into said socket and also contracts said split ring.

8. A connector comprising a split ring having its inner surface oppositely tapered

toward its margins and having substantially parallel end members, one of said members having a tapered socket, a tapered plug fitted in said socket, and binding means carried by the other member and operatively engaging said plug, whereby said binding means operates to draw said plug into said socket and also contracts said split ring.

WARD S. PERRY.
